UNITED STATES PATENT OFFICE

2,595,312

BUCKET ELEVATOR AND FEED MEANS
THEREFOR

Henry H. Talboys, Milwaukee, Wis., assignor to
Nordberg Manufacturing Company, Milwaukee,
Wis., a corporation of Wisconsin

Application February 2, 1949, Serial No. 74,193

6 Claims. (Cl. 198—98)

1

My invention relates to an improvement in ballast handling mechanism and has for one purpose to provide a ballast screening assembly.

Another purpose is to provide a ballast screening assembly which may readily be accommodated on a single car and which is of relatively light weight.

Another purpose is to provide a ballast screening assembly with simple, compact and efficient means for receiving dirty ballast, for returning cleaned ballast to the right-of-way, and for disposing of the fines and foreign material.

Another purpose is to provide an improved elevator for use with screening equipment.

Another purpose is to provide an improved assembly for removing the screened fines from the railroad right-of-way.

Other purposes will appear from time to time in the course of the specification and claims.

I illustrate the invention more or less diagrammatically in the accompanying drawings wherein:

Figure 1 is a vertical partial longitudinal section through the unit;

Figure 2 is a horizontal section along the lines 2—2 of Figure 1;

Figure 3 is a vertical section along the lines 3—3 of Figure 1.

Referring to the drawings, 1 generally indicates the rails of a track, upon which the below-described screening unit may move. 2 generally indicates the lower portion of a car frame, which may include longitudinal and transverse elements, not separately identified. Upwardly extending from the base frame 2 of the car are a plurality of vertical structure members or supports 3, which are shown as connected at their upper ends by transverse channels or elements 4. The lower car frame 2 may be suitably supported on the rails 1. I illustrate, however, suitable rail engaging wheels 6.

Referring to Figure 1, illustrate diagrammatically a multi-deck screen assembly generally indicated at A, the details of which do not of themselves form part of the present invention. I may, for example, employ vibratory screens which may be vibrated by any suitable vibratory rotor or rotors, not herein shown.

It will be understood that the herein described and shown ballast screening assembly may be used to process dirty ballast. Such ballast may be excavated by hand or by suitable mechanical equipment and may, by means not herein shown, be fed to the screen assembly A.

Beneath the screen assembly A is the endless conveyor 40, which is positioned and adapted to

2

receive the fines which pass through the screen assembly. The endless conveyor 40 passes at its ends about suitably driven rollers 41. 45 indicates any suitable bottom supporting rollers 5 mounted on the conveyor frame or support 46, which extends longitudinally of the unit and which may rest upon the bottom car frame 2.

It will be understood that the oversize is eliminated by the screen assembly A and delivered 10 where desired, whereas the fines pass to the left along the endless conveyor 40, referring to the position in which the parts are shown in Figure 1. The fines are received in a suitable hopper, box or pan 47, into which extends the below described 15 elevator.

The hopper, box or pan 47 is shown as rotatably mounted. It may, for example, have a circumferential bottom track 48 surrounded by a fixed track 49, the two tracks having therebetween any suitable balls or rollers 50. Preferably, the hopper, box or pan 47 is continuously rotated during use. It may be driven by any suitable motor diagrammatically indicated at 46a, through the gear reduction 49a, the pinion lines 50 and the gear 51, the latter being mounted on the bottom of the hopper, box or pan 47. Thus the hopper, box or pan 47 is continually rotated and the material fed thereto, by the belt 40, is rotated and distributed and is prevented 25 from concentrating at the point of its delivery from the conveyor 40.

52 indicates an upper turntable member which rotates in surrounding tracks 53 provided with suitable balls or rollers 54. 55 is a top frame 35 structure or platform which may be rotated with the turntable 52 and is independent of the rotation of the hopper, box or pan 47. Although the hopper, box or pan 47 rotates during the use of the device, the platform 55 may be positioned 40 at any desired position for the purposes which will later appear. The platform 55 is shown as carrying a motor 56.

57 indicates a generally vertically extending frame structure carrying upper sprockets 58 and 45 lower sprockets 59, about which passes the endless belt or chain conveyor 60, which carries buckets 61. The sprockets 58 may be mounted 50 on the shaft 65 which, in turn, is driven by any suitable belt or connection 66 from the motor 56. It will be noted that a deflecting scraper 67 is mounted on the lower portion of the frame 57 and causes an accumulation of material in 55 response to rotation of the hopper, box or pan 47 at a proper position to be picked up by the buckets 61, when the hopper, box or pan 47 is

rotated in the direction of the arrow shown in Figure 3.

Any suitable feed receiving means may be provided for the upper end of the elevator. I illustrate a receiving spout 70 into which the buckets 61 deliver the material. The material so delivered passes to the endless conveyor 71, on the boom 72, the endless conveyor being driven, for example, by a chain 73 passing around a sprocket 74 on the countershaft 75 of the boom 72 and passing, at its other end, about the sprocket 76 on the shaft 65 at the upper end of the elevator frame 57.

The boom 72 may be suitably supported from any suitable upwardly extending structure or mast 80 on the rotatably adjustable platform 55, its end being controlled, for example, by the cable 81 passing around a pulley 82 at the upper end of the mast and extending under an actuating or hoist drum 83 of the mast 80. The drum 83 may be actuated manually or otherwise to adjust the boom at any desired height.

It will be understood that the boom, with the platform 55, may be rotated about a vertical axis or may be located at various positions about the vertical axis of the turntable 52 without interfering with the normal delivery of material from the belt or conveyor 40 to the hopper, box or pan 47 and its removal from the hopper, box or pan 47 by the buckets 59.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my specific disclosure.

The use and operation of my invention are as follows:

In the form of my invention as herein shown, I may deliver ballast to be cleaned to a suitable screening assembly. It is desirable to eliminate fines from the ballast and to return to the right-of-way the ballast particles or pieces of proper size.

In the structure herein shown, it will be understood that any suitable screening assembly A separates the undersize from the oversize and delivers the undersize or fines to the endless conveyor 40. The oversize may be returned directly to the right-of-way by any suitable equipment or attachments not herein shown. The undersize is delivered by the endless conveyor 40 to the rotating hopper, box or pan 47.

The rotation of the hopper, box or pan 47 causes the material to accumulate against the scraper 67. The scraper 67, which is mounted on the elevator frame 57, is always located at the proper position to accumulate material to be picked up by the buckets 61. The belt 60 is preferably driven at sufficient speed so that the material is delivered laterally at the top of the elevator at sufficient velocity to travel to and be received upon the spout 70, which delivers it to the receiving end of the discharge conveyor 71.

By rotation of the platform 55 about the vertical axis of the turntable 52, the boom 72 may be set to deliver the undersize at any desired point or area. It may be delivered to another car for disposal or it may be wasted to the side of the right-of-way. As a matter of convenience,

I illustrate the motor 56 as mounted on the platform 55 and as driving both the elevating belt or conveyor 60 and the disposal conveyor 71. Any suitable means may be employed for rotating the platform 55 to any desired position of adjustment.

It will be understood that the turntable structure 52 may be rotatably adjusted to any desired angle. When the screen car is being conveyed from place to place along the tracks, it is advantageous to have the parts in the position in which they are shown in Figures 1 and 2, with the conveyor boom 72 aligned with the axis or center of the car. However, it can be swung for use over either side of the right-of-way or over an adjacent car to the rear.

I claim:

1. In a feed and elevating assembly, a pan and means for rotating it about a generally upright axis, a conveyor adapted to deliver material to the interior of the pan, a turntable assembly mounted for rotational adjustment generally coaxially with the pan, a frame positioned on said turntable assembly, an endless bucket conveyor on said frame and means for driving it, said bucket conveyor having buckets extending into the pan in the course of their movement, and a laterally extending discharge conveyor adjustable in unison with said turntable assembly and adapted to receive material from said bucket conveyor.

2. The structure of claim 1, characterized by and including a boom on said turntable assembly on which said discharge conveyor is supported.

3. The structure of claim 1, characterized by and including a motor mounted on said turntable assembly and driving connections between said motor and said bucket conveyor and discharge conveyor.

4. The structure of claim 1, characterized by and including a scraper extending into said pan and mounted on said frame.

5. In a feed and elevating assembly, a pan and means for rotating it generally continuously about a generally upright axis, a scraper in said pan, adapted to concentrate, at a predetermined area of concentration, material fed to the pan, and a bucket elevator including a bucket chain having buckets positioned to pass through said area of concentration, said bucket elevator being adjustable about a generally upright axis, said scraper being mounted for adjustment within said pan when the elevator is adjusted.

6. The structure of claim 5, characterized by and including a turntable assembly on which said bucket elevator is mounted, and from which it depends, and a boom on said turntable assembly positioned and adapted to receive the discharge from the upper end of said bucket conveyor.

HENRY H. TALBOYS.
